UNITED STATES PATENT OFFICE.

GEORGE I. LEONARD, OF CHICAGO, ILLINOIS.

CONDENSER FOR ICE MACHINES.

Application filed January 8, 1927. Serial No. 159,881.

In any mass of pipes laid rather closely together, in directing currents of air against such a mass, many conflicting air currents are set up, with the result that a great deal 5 of the effectiveness is lost.

In my invention I make use of the natural stream lines principle, by creating an air suction past a refrigerant receiver, lengthwise of a line of pipes and past a gas receiving tank, all within a conduit formed by a hollow base on which rests a compressor, a fan and a motor, the motor and fan being 10 within a superimposed passageway. This principle allows me to construct a counter 15 current air cooled condenser.

In the accompanying drawings, Figure 1, shows a motor direct connected to a fan and compressor and mounted upon a hollow base shown in vertical cross section. Covering 20 the fan and compressor is a hood for directing air currents which enter from the top of base through an orifice. A pipe leads from the discharge side of the compressor to a gas receiving tank within the base and from 25 which extend a multiplicity of pipes which connect at their other end to a condensate receiver. An air intake port is located at this end of the base.

In Figure 2 of Sheet 2 is shown a horizontal cross section of a hollow base containing 30 a gas receiving tank as in Figure 1, and leading from this are lines of pipe consisting of straight runs with reverse bends; but having the straight runs crosswise of the base. 35 At the other end these pipes connect to the condensate receiver. The base in this case also has a suction air intake located next to the condensate receiver. In Figure 1, I have shown a base 1 on which is mounted a motor 40 2, direct connected to a coupling 3 and a fan 4, and through the shaft 5 to a pump 6. The pump 6 shows a suction port 7 and in dotted lines the discharge port 8 to which is connected a pipe 9 that attaches at its lower 45 end to a tubular manifold 10.

Branching from the manifold 10 are shown four (4) lines of pipe 11, other lines of pipes supposedly lie back of those shown. These pipes enter at their other end the receiving chamber 12 where liquid refrigerant 50 is caught after condensation. Surrounding the fan and the pump is a casing 13 which rests on the base. At 14 is a rectangular opening in the top of the base which extends 55 to nearly the width of the casing 13, and

through which air is drawn. At 15 is an opening in the sides of the base of sufficient size to pass all the air that the fan is capable of throwing. It will be observed that as the fan 4 is rotated in a right hand direction it will give rise to an area of low pressure on the pump side, this will result in air entering the open portion of the base at 15 and it will pass in the direction of the arrows 16, longitudinally with the pipes 11, 60 out through the opening 14 and finally out of the contracted opening surrounding the fan. The compressed gas coming from the pump in tube 9, after entering manifold 10 will then be distributed to the pipes 11, following direction of arrows 20, and as it condenses will pass into the container 12, thus setting up a current within the pipes in a reverse direction to the passage of the air through the base. 65

On Sheet 2, Figure 2, is shown a top view of another arrangement of pipes, but in which the principle governing is the same.

I have used the same numbers as on Figure 1, except that the opening 17 in manifold 10 and the dotted lines 18 show the position of the rectangular orifice 14. In both figures, a plate 19 extends from the manifold end of the base to the side opening 15 and underlies the pipes, in order to confine the 85 air current more closely to the channel in which the pipes lie. In Figure 2 the pipe 9 is supposed to enter the manifold 10 at 17, the arrows 20 show the direction of the flow of the gas in the pipes 11. In this case 90 each pipe has a number of reverse bends, but the gas becomes successively cooler as it approaches the opening 15, and finally enters the container 12. I have, for clarity, only shown two runs of pipe as they lie one 95 above the other.

The air current shown by arrows 16 is thus really in reverse direction to the general direction of the gas within the pipes, and after traversing the pipes flows upward through 100 the opening 14 shown by dotted lines 18 into the chamber surrounding the pump. By these arrangements a decided gain in efficiency is effected, as it produces so rapid a current of air past the condenser pipes that 105 a much smaller length of pipe is necessary to produce an equivalent amount of cooling, and as the coldest air in the systems passes in at the container end of the line, and the temperature at this end establishes the 110

amount of pressure that must be carried, it therefore effects a double economy in cost of construction and in operating expense.

I hereby make reference to an application 5 Serial No. 159,882, filed Jan. 8, 1927 for a patent for method of cooling air cooled refrigerating machines.

Therefore I claim:

1. The combination with an air conduit 10 having admission and discharge ports; of means for effecting the passage of air into the admission port, through the conduit and through the discharge port; a gas receiving chamber; a condensate receiving chamber; 15 piping within said conduit extending substantially along the path of and following through said conduit and connecting said chambers; said chambers and the piping connecting them being arranged to direct the 20 flow of gas and condensate to the condensate receiving chamber oppositely to the direction of flow of air along the piping; and a pump connected with the gas receiving chamber to force gas thereunto and into the piping connecting the chambers.

2. The combination with an air conduit 25 having admission and discharge ports; of means for effecting the passage of air into the admission port, through the conduit and 30 through the discharge port; a gas receiving chamber within said conduit; a condensate receiving chamber; piping within said conduit extending substantially along the path of and following through said conduit and 35 connecting said chambers; said chambers and the piping connecting them being arranged to direct the flow of gas and condensate to the condensate receiving chamber oppositely to the direction of flow of air along the pip-

ing; and a pump connected with the gas receiving chamber to force gas thereunto and into the piping connecting the chambers. 40

3. The combination with an air conduit having admission and discharge ports; of means for effecting the passage of air into 45 the admission port, through the conduit and through the discharge port; a gas receiving chamber, a condensate receiving chamber within said conduit; piping within said conduit extending substantially along the path 50 of and following through said conduit and connecting said chambers; said chambers and the piping connecting them being arranged to direct the flow of gas and condensate to the condensate receiving chamber oppositely 55 to the direction of flow of air along the piping; and a pump connected with the gas receiving chamber to force gas thereunto and into the piping connecting the chambers.

4. The combination with an air conduit 60 having admission and discharge ports; of means for effecting the passage of air into the admission port, through the conduit and through the discharge port; a gas receiving chamber within said conduit; a condensate 65 receiving chamber within said conduit; piping within said conduit extending substantially along the path of and following through said conduit and connecting said chambers; said chambers and the piping connecting them being arranged to direct the 70 flow of gas and condensate to the condensate receiving chamber oppositely to the direction of flow of air along the piping; and a pump connected with the gas receiving chamber to 75 force gas thereunto and into the piping connecting the chambers.

GEORGE I. LEONARD.
